(57) **CLAIM**

The ornamental design for a mounting device, as shown and described.

DESCRIPTION

FIG. 1 is an environmental perspective view of a mounting device in accordance with our new design;

FIG. 2 is another perspective view thereof;

FIG. 3 is a bottom perspective view thereof;

FIG. 4 is an elevation view thereof;

FIG. 5 is a top plan view thereof; and,

FIG. 6 is a bottom plan view thereof.

The broken lines in the figures illustrate environmental structure only and form no part of the claimed design.
